PAUL KIRCHER AND JULIUS J. GRUENFELD, JR., OF CHICAGO, ILLINOIS, ASSIGNEES
TO MASSEY CONCRETE PRODUCTS CORPORATION, OF CHICAGO, ILLINOIS, A CORPO-
RATION OF VIRGINIA.

POLE AND STEP THEREFOR.

1,369,114.

Specification of Letters Patent. Patented Feb. 22, 1921.

Application filed May 21, 1918. Serial No. 235,758.

To all whom it may concern:

Be it known that we, PAUL KIRCHER and JULIUS J. GRUENFELD, Jr., both citizens of the United States, and both residing at Chicago, county of Cook, and State of Illinois, have invented certain new and useful Improvements in Poles and Steps Therefor, (Case #2,) of which the following is a specification.

10 This invention relates to poles such, for example, as concrete poles, and it has for one of its primary objects the provision of a pole of this character having improved means whereby a lineman can climb the pole 15 by the use of the ordinary climbing spurs. The invention also contemplates the disposition of the steps with reference to the pole in such manner that they will present no interference to the use of certain classes of 20 clamp climbing devices which are adapted to embrace the pole and clamp themselves in position thereon when pressure is applied to the clamps. We also propose to so arrange the steps that the poles may be 25 shipped without liability of injury or breakage.

In general, our invention contemplates a simple form of step which, while readily permitting of the insertion of the spurs of a 30 lineman, is nevertheless of such a character that it affords little or no assistance to an unauthorized person who attempts to climb the pole.

The foregoing, together with such other 35 objects as may hereinafter appear, are obtained by means of a construction the preferred embodiment of which we have illustrated in the accompanying drawings, wherein—

40 Figure 1 is a diagrammatic illustration of a portion of a pole to which our invention has been adapted; Fig. 2 is a side elevation of a portion of the pole, drawn on an enlarged scale and showing one of the steps; 45 Fig. 3 is a section taken on the line III—III of Fig. 2; Fig. 4 is a section taken on the line IV—IV of Fig. 2; and Figs. 5 and 6 are sectional views of parts of the mold form details utilized in forming the step-receiving cavities in the surface of the pole and in holding the steps in position during the formation of the pole.

Our invention is capable of use in connec-

tion with solid or hollow concrete poles, although in the drawings we have illustrated 55 its application to a hollow type of pole.

Referring now to the drawings, the pole is indicated as a whole by the reference letter A, and it is provided on alternate sides with recesses 7 in which the outer looped 60 ends 8 of the pole steps B, which are embedded in the body of the pole, are disposed. The recesses 7 have a greater length than width, with all surfaces curved, as indicated in the drawings, so that the recesses will be 65 self-draining in order to prevent the freezing which might otherwise occur in winter weather. The recesses are also very shallow and their formation is such that the spurs may be readily inserted in the looped ends 70 of the steps, although the recesses themselves will not present a gripping surface by means of which an unauthorized person would be materially assisted in climbing the 75 pole. In this connection it is to be noted that the looped ends 8 of the steps are substantially flush with the periphery of the pole and have a width just about sufficient to receive the spurs but insufficient to permit of 80 the gripping of the loops by two fingers.

The steps B are preferably composed of wire and are of U-shape with the end portions 9 of the legs 10 bent substantially at right angles as shown in Figs. 2, 3, and 4. 85 The method of positioning and holding the steps during the making of the poles (either by the centrifugal or any other preferred method) will now be described, attention being directed particularly to Figs. 5 and 6.

In such figures we have shown a portion of the pole form C, such form being preferably composed of metal. Secured to the inner surface of the form and on alternate sides thereof, are a plurality of pairs of companion cores 11 and 12 which are adapted to form the recesses 7 hereinbefore described. The core members are secured to the form by means of the studs or screws 13. 95 The core members are preferably composed of cast iron and are provided with registering grooves 14 formed in the meeting faces of the cores and adapted to receive the looped end portion 8 of a step and support the step 100 during the formation of the pole. After the pole has been formed, the studs 13 are re-

moved, after which the mold C is then stripped from the pole. The core members 11 and 12 can thereafter be readily removed from about the pole steps, leaving the step 5 embedded in the concrete. It will be noted that the loops 8 of the steps are disposed below the middle of the recesses 7 to facilitate the introduction of the lineman's spurs.

From the foregoing it will be clear that 10 we have provided a simple and inexpensive form of pole and step, which is of such a character that the steps are protected against injury during shipment; do not interfere with the use of climbing clamps; present no material assistance to an unauthorized person attempting to climb the pole; and are to 15 some extent protected from the weather. Other advantages will be apparent to those familiar with the art.

20 We claim:—

1. A pole having longitudinally spaced step recesses in the surface thereof, and

steps having heads which are disposed in said recesses.

2. A pole having longitudinally spaced 25 step recesses in the surface thereof, and steps having heads which are disposed in said recesses substantially flush with the outer surface of the pole.

3. A pole having longitudinally spaced 30 step recesses formed in the surface thereof, and steps embedded in said pole and having looped ends disposed in said recesses.

4. A pole having a plurality of longitudinally spaced recesses in the surface thereof, 35 and U-shaped steps embedded in the pole with their looped ends projecting laterally in said recesses and having their end portions extending at an angle with respect to 40 the looped ends.

In testimony whereof, we have hereunto signed our names.

PAUL KIRCHER.

JULIUS J. GRUENFELD, JR.
